UNITED STATES PATENT OFFICE

2,571,339

DRESSER MOUNTING

Leonard O. Carlsen, Rochester, N. Y., assignor
to Gleason Works, Rochester, N. Y., a corpora-
tion of New York

Application January 28, 1949, Serial No. 73,356

6 Claims. (Cl. 125—11)

1

The present invention relates to machines of the generating type for grinding spiral bevel and hypoid gears, and particularly to means for mounting the wheel-dressing mechanisms on such machines. In a still more specific aspect, the invention relates to a spiral bevel and hypoid gear grinding machine of the type disclosed in the pending U. S. patent application of William C. Critchley and Herman A. Male, Serial No. 56,144, filed October 23, 1948, which has issued as Patent No. 2,566,402, dated September 4, 1951, and to means for mounting the wheel-dressing mechanism on such a machine.

In spiral bevel and hypoid gear grinders of the generating type, the tool commonly used is a rotary annular grinding wheel. This wheel is mounted on an oscillatory cradle that is rotated in time with the rotation of the work to produce the generating motion and to cause the wheel to grind correct tooth profiles on the work. To grind gears of different spiral angles, the wheel has to be adjusted on the cradle radially and angularly about the cradle axis.

In conventional spiral bevel and hypoid gear grinders of the generating type, the dressing mechanism is mounted on the cradle so that it is adjustable with the wheel. This has made it difficult to balance the cradle in all of the different positions to which the dressing mechanism may be adjusted about the axis of the cradle. The speed at which the grinding operation can be performed has heretofore been limited, therefore, because if the cradle is oscillated at high speed vibrations will be set up due to its unbalanced condition.

Because the dressing mechanism has heretofore been mounted on the cradle and adjusted with the wheel, guarding of the wheel has been difficult, and, moreover, the connection of the dressing mechanism with its source of power has been complicated.

All of these difficulties are increased in a grinding machine of the character disclosed in the Critchley and Male application referred to above, for in this machine, the adjustment of the grinding wheel for spiral angle is achieved in part by rotary adjustment of a carrier whose axis is eccentric to the axis of the cradle and angularly inclined thereto. Were the dressing mechanism to be mounted directly on the cradle in this machine, the dressing mechanism would not only have to be adjusted to different angular positions when the wheel is adjusted for different spiral angles, but would also have to be adjusted

2

to different axial positions relative to the cradle axis for any such adjustment of the wheel.

A primary object of the present invention is to provide a mounting for a dressing mechanism for a spiral bevel and hypoid gear grinding machine of the generating type through which the weight of the dressing mechanism may be supported independently of the cradle so that the cradle may be operated at high speed for generating the tooth profiles without the dressing mechanism in any way affecting the balance of the cradle or tending to cause vibration.

Another and concomitant object of the invention is to provide a mounting for the dressing mechanism on a spiral bevel and hypoid gear grinding machine of the generating type in which the wheel may be adjusted for spiral angle independently of the dressing mechanism and in which the dressing mechanism will have substantially the same position with reference to the cradle in all positions of adjustment of the wheel so that the cradle may readily be balanced.

Other objects of the invention will be apparent hereinafter from the specification and from the recital of the appended claims.

The invention has been illustrated in the drawings as applied to a gear grinding machine of the type described in the Critchley and Male application above mentioned, and it will be described herein in connection with such a machine. It will be understood, however, that it is not limited to such use.

In the drawings:

Fig. 1 is a fragmentary view of a machine built according to the Critchley and Male application, looking at the face of the wheel-carrying cradle and of the upright which supports the same, and showing a dresser support which is constructed according to one embodiment of the invention, mounted in operative relation to the wheel;

Fig. 2 is a fragmentary side elevational view looking from the left of Fig. 1, and showing the positions of the parts when the wheel is in a zero position of its adjustment;

Fig. 3 is a fragmentary axial sectional view showing the mounting of the grinding wheel and further illustrating the mounting for the dresser mechanism;

Fig. 4 is a more or less diagrammatic view showing the wheel adjusted to a different position from that of Figs. 2 and 3;

Fig. 5 is a fragmentary detail sectional view showing the connection of the bar, which connects the dresser support to the upright or frame of the machine, with the upright or frame; and

Fig. 6 is an elevational view of the carrier or ring upon which the dressing mechanism is supported.

Only so much of the machine of the Critchley and Male application is shown in the drawings as is necessary to an understanding of the present invention.

The grinding wheel **W** of this machine is secured to the armature shaft **10** (Fig. 3) of a motor **11** which is mounted on an axially reciprocable type sleeve bearing **12** in a slide **14**. This slide is adjustable, as described in the application mentioned, to compensate for wear of the grinding wheel.

The slide **14** and bearing **12** are both mounted in a circular carrier **15**. This carrier is mounted upon plain bearings **16** and **17** in a swivel head **18** for angular adjustment about an axis inclined to the axis of the grinding wheel and to the axis of the swivel head. The carrier may be adjusted angularly in the swivel head by rotation of a stub shaft **19** which carries a spur pinion **20** that meshes with a spur gear **21** which is secured to the carrier by screws **22**. The swivel head **18** is journaled on plain spaced bearings **24** and **25** for rotatable adjustment in a drum **26** about an axis which is parallel to the axis of the drum. The adjustment of the swivel head **18** may be affected by rotation of the stub shaft **27** which carries a spur pinion **28** that meshes with a spur gear **29** that is secured to the swivel head by screws **30**. The drum **26** itself is mounted for rotatable adjustment on a plain bearing **32** in the cradle **34** for adjustment about an axis parallel to the axis of adjustment of the swivel head **18**. Cradle **34** itself is journaled on roller bearings **35** in an upright or support **36**, the angular adjustment of the cradle being affected about an axis which is offset from but parallel to the axis of the drum **26**.

The dresser mounting, which constitutes the present invention, comprises a support or ring member **40** that is held by an annular gib **41** and screws **42** upon a second ring member **44**. The latter is secured by screws **45** to a third ring member **46** that in turn is secured by screws **47** to the carrier **15**. The ring **44** constitutes a support upon which the support or ring member **40** is rotatable as the carrier **15** rocks about the cradle axis in the oscillation of the cradle. Support **40** is coaxial with wheel spindle **10**.

Support **40** is connected to upright **36** by an adjustable turnbuckle member or bar **57**. This turnbuckle member is mounted at one end **58** on a ball member **60**, and at its opposite end **59** on a ball member **61** (Figs. 2 and 3). Ball member **60** is secured on a stud **62** (Fig. 5) by a disc **66** and by a screw **67** which holds the disc **66** in place. Stud **62** threads into a sleeve member **64**. Sleeve member **64** is axially adjustable in a bushing **68** (Fig. 2) that is secured in upright **36** by screws **69**. Sleeve member **64** is securable in any adjusted position by a set-screw **70**. Ball member **61** is mounted, similar to ball member **60**, on a stud **63** that threads into a sleeve **65** which is secured in support **40**.

The parts are shown in Figs. 2 and 3 with the grinding wheel in a zero position of its angular adjustment. Here the axis of the wheel spindle **10** is parallel to the axis of the cradle **34** and coincides with the axis of the eccentric drum **26**. It is also parallel and eccentric to the axis of the swivel head **18**. The axis of the swivel head is inclined to and intersects the axis of the carrier **15**.

In Fig. 4 there is shown diagrammatically an extreme position of adjustment of the grinding

wheel. Here the wheel carrier **15** has been swung about the axis **v** of the swivel head **18** through an angle of 180° from the position shown in Fig. 2. Axis **t** of the wheel spindle has been swung far enough about the center **a** of intersection of the two axes **t** and **v** that the axis **v** of the swivel head bisects the angle between the axis **t** and the axis **z** of the eccentric drum **26**. The plane **T** of the tip of the grinding wheel is now inclined to the central plane **P** of the machine.

It will be noted that in this adjustment, the bar **57**, which connects the ring support **40** with upright **36**, prevents the dresser mechanism **50** from shifting position with the wheel and carrier **15**. In this adjustment, therefore, the supporting ring **44** revolves in the ring support **40**, and the turnbuckle member **57** swings angularly so that it may accommodate itself to the new angular position of the grinding wheel. In the generating operation, also, the ring member **40** rocks back and forth on the supporting ring **41** and the turnbuckle **57** rocks back and forth on the two ball joints which connect its opposite ends to the ring **40** and the column **36**, respectively. Regardless of adjustment of the grinding wheel or of oscillation of the cradle, then, the dressing mechanism remains in relatively fixed position. It does not shift position on the cradle; and so far as the dressing mechanism is concerned, then, the cradle remains in balance. Thus, the cradle may be operated at high speed.

The sleeve member **64** is adjusted to suit the angular position of the grinding wheel and then locked in place by the set-screw **70**. The lateral adjustment of dresser mechanism **50** on ring support **40** permitted by tongue **52** allows of positioning the diamond for wheels of different diameters. Turnbuckle **57** is adjusted to adjust the length of the connecting bar to compensate for lateral adjustment of the dresser mechanism on support **40**.

While the invention has been described in connection with a particular embodiment thereof, it will be understood that it is capable of further modification, and this application is intended to cover any variations, uses, or adaptations of the invention following, in general, the principles of the invention, and including such departures from the present disclosure as come within known or customary practice in the gear art and as may be applied to the essential features hereinbefore set forth and as fall within the scope of the invention or the limits of the appended claims.

Having thus described my invention, what I claim is:

1. In a machine for grinding gears in a generating operation, the combination with a cradle, a housing in which the cradle is oscillatably mounted, a carrier angularly adjustable on the cradle about an axis offset from the axis of the cradle, and a grinding wheel journaled rotatably in said carrier, of a support rotatably mounted on said carrier, a bar pivotally connected at one end to said support and pivotally connected at its opposite end to the housing, and wheel dressing mechanism mounted on said support.

2. In a machine for grinding gears in a generating operation, the combination with a cradle, a housing in which the cradle is oscillatably mounted, a carrier angularly adjustable on the cradle about an axis offset from and angularly disposed to the axis of the cradle, and a grinding wheel journaled rotatably in said carrier with its axis inclined to the axis of the carrier, of a support rotatably mounted on said carrier for rota-

tion about an axis coinciding with the axis of the wheel, means connecting said support to said housing, and wheel dressing mechanism mounted on said support.

3. In a machine for grinding gears in a generating operation, the combination with a cradle, a housing in which the cradle is oscillatably mounted, a carrier angularly adjustable on the cradle about an axis offset from and angularly disposed to the axis of the cradle, and a grinding wheel journaled rotatably in said carrier with its axis inclined to the axis of the carrier, of a support rotatably mounted on said carrier for rotation about an axis coinciding with the axis of the wheel, a bar having a universal joint connection at one end to the support and having a universal joint connection at its opposite end to the housing, and wheel dressing mechanism mounted on said support.

4. In a machine for grinding gears in a generating operation, the combination with a cradle, a housing in which the cradle is oscillatably mounted, a carrier angularly adjustable on the cradle about an axis offset from and angularly disposed to the axis of the cradle, and a grinding wheel journaled rotatably in said carrier with its axis inclined to the axis of the carrier, of a support rotatably mounted on said carrier for rotation about an axis coinciding with the axis of the wheel, a ball-headed pin slidably mounted in said housing for adjustment in the direction of the axis of the cradle, a bar mounted at one end on the head of said pin, a second ball-headed pin on which the opposite end of the bar is mounted, said second ball-headed pin being secured in said support, and wheel dressing mechanism mounted on said support.

5. In a machine for grinding gears in a generating operation, the combination with a cradle, a housing in which the cradle is oscillatably

mounted, a carrier angularly adjustable on the cradle about an axis offset from and angularly disposed to the axis of the cradle, and a grinding wheel journaled rotatably in said carrier with its axis inclined to the axis of the carrier, of a support rotatably mounted on said carrier for rotation about an axis coinciding with the axis of the wheel, a ball-headed pin slidably mounted in said housing for adjustment in the direction of the axis of the cradle, a bar mounted at one end on the head of said pin, a second ball-headed pin on which the opposite end of the bar is mounted, said second ball-headed pin being secured in said support, and wheel dressing mechanism mounted on said support for lateral adjustment thereon, said bar being adjustable as to length.

6. In a machine for grinding gears, the combination with a housing, a supporting member adjustable angularly in said housing, a carrier angularly adjustable on said member about an axis angularly disposed to the axis of adjustment of said member, a rotary spindle journaled in said carrier with its axis inclined to the axis of adjustment of said carrier, and a grinding wheel secured to said spindle, of a support rotatable on said carrier about an axis coinciding with the axis of the spindle, means directly connecting said support to the housing, to permit movement of the support independently of the supporting member, carrier, and spindle and wheel dressing mechanism mounted on said support.
